UNITED STATES PATENT OFFICE.

SAMUEL BROWN, OF ST. LOUIS, MISSOURI.

GUMMED-TAPE-MOISTENING MACHINE.

1,110,667.

Specification of Letters Patent. Patented Sept. 15, 1914.

Application filed November 3, 1913. Serial No. 798,916.

To all whom it may concern:

Be it known that I, SAMUEL BROWN, citizen of the United States, residing at St. Louis, State of Missouri, have invented 5 certain new and useful Improvements in Gummed-Tape-Moistening Machines, of which the following is a full, clear, and exact description, reference being had to the accompanying drawings, forming a part 10 hereof.

My invention has relation to improvements in gummed-tape moistening machines; and it consists in the novel details of construction more fully set forth in the specification and pointed out in the claim. 15

In the drawings, Figure 1 is a top plan of the machine, with parts broken away; Fig. 2 is a vertical longitudinal section on the line 2—2 of Fig. 1; Fig. 3 is a vertical cross-section on the line 3—3 of Fig. 1; Fig. 4 is a vertical cross-section on the line 4—4 of Fig. 1; and Fig. 5 is an enlarged vertical sectional detail of the members forming the passage-way for the tape opposite the apron 25 carried by the rear wall of the water-tank.

The present invention is directed to machines in which strips of paper gummed on one side are automatically moistened on the gummed side with the withdrawal of the 30 paper from the machine, the paper being usually in the form of a roll rotatably mounted on a spindle, and from which any length of strip may be pulled off and severed. Such moistened strips are used for 35 sealing packages and bundles in business and commercial houses, as well understood in the art.

The object of my invention is to provide 40 means for so directing and guiding the strip after it leaves the roll, that the end of the strip left projecting above the moistening roll after a given section has been severed, will not come in contact with said roll, so that the end of the paper will always be dry, 45 and when seized by the clerk for purposes of pulling or reeling off the next section, it will not stick to the fingers or tear off by being weakened as a result of absorption of an excess of moisture.

50 The advantages of the structural features will become apparent from a detailed description of the invention which is as follows.

Referring to the drawings, 1, 1, represent 55 the side basal members of a suitable supporting frame, the same terminating at one end

in standards 2, 2, for the support of the spindle 3, which carries the roll of tape or paper strip, and at the opposite end in a basin, liquid container or water-tank 4. The ends of the spindle 3 rest in the upper terminal recesses *b*, *b*, of the standards 2 as shown. Passed loosely over the spindle are the bosses *e*, *e'*, of the heads or spiders 5, 5', which engage the roll of tape or paper *h* from opposite sides to guide the same in the unrolling thereof, the tape or strip being gummed on the under side or that facing the bottom of the supporting frame. The spiders or heads 5, 5', are preferably composed of a series of radial arms as shown and of a length to 65 engage the entire face of the roll mounted between the heads. The boss *e* of one of the heads is provided with a set-screw *s* by which, when the head is once adjusted along the spindle, the said head may be clamped to the spindle. The boss *e'* of the opposite or yielding head 5' is provided with a socket 6 for receiving one end of a compression spring 7 coiled about the spindle, the opposite end of the spring being in engagement 70 with a ring 8 slidable along the spindle and provided with a set screw *s'* by which it may be clamped to the spindle when once properly adjusted to cause the spring 7 to impose the desired pressure or tension on the head 5' 75 bearing against the roll. The ring 8 is preferably provided with a reduced portion 8' about which the spring is coiled, the end of the spring bearing against the annular shoulder formed on the inner face of the ring 80 proper around said reduced portion. 90

Mounted across the water tank 4, and supported by trunnions 9 resting in bearings 10 formed on the side walls of the tank, is a peripherally and longitudinally grooved cylinder or moistening drum 11, the grooves *m* serving to pick up the necessary water to moisten the tape or strip as the latter is passed over the drum in the withdrawal thereof from the roll. Spanning the drum 11 at a point rearward of the axis of rotation thereof, and secured to the sides of the tank 4, is an inverted-U-shaped frame 12, to the upper horizontal member of which is secured the cutter-blade or knife 13, or equivalent cutter. The rear upper portion of the periphery of the moistening drum is protected by an apron 14 secured to the upper curved extension of the rear wall of the water-tank, the apron lying close to the drum 110

and operating to spread a film of water over and across the section of the drum immediately beneath the free edge of the apron, said film being spread effectively across the 5 full width of the gummed surface of the tape as the latter is pulled over the drum (the drum rotating freely in response to the tape advanced thereover).

Disposed across the machine between the 10 rear extensions of the side walls of the tank 4, and immediately behind the rear wall of the tank are cross-bars or rods 15, 16, respectively, the rod 15 serving as an anchor for the fixed end of a flexed resilient shield 15 or guide sheet 17, the end secured to the rod 15 being wrapped or bent around the rod as shown, whence the sheet is brought under the rod 16 and then run upward in substantial conformity to the curvature of the rear 20 wall of the tank 4, the tape passing between said wall and guide sheet. The upper end of the rear wall of the tank has formed across the same a substantially angular groove *a*, the free end of the guide-sheet being bent to form an inner forwardly inclined portion *t* terminating in an upturned lip *u*, which, by reason of the resiliency inherent in the sheet 17, is forced into engagement with the front vertical wall of the 25 groove *a*, the tape or strip being thus obliged to pass between the lip *u* and the front wall of the groove, and in its passage between the parts, the strip is more or less gripped, and deflected away from the apron 14 and from 30 the drum 11. A strip gummed as heretofore pointed out is more or less stiff and resiliency, and when bent from its course and then released, it tends to recoil or spring back to its original position. It is this recoil which is taken advantage of in the present invention, thereby dispensing with the necessity of special devices for moving the strip away from the moistening drum after the severing of any section of paper from 35 the roll.

One arm of each head 5, 5', is extended sufficiently to reach the rod 15, the heads being turned on the spindle so as to bring these arms into locking engagement 50 with the rod. In practice the ends of these arms are provided with jaws *w* which embrace the portion of the sheet 17 folded about the rod, and thus lock the heads to the rod, and prevent rotary displacement thereof.

55 By the construction as described, the head 5 which engages one face of the roll *h* becomes firmly locked to the spindle 3, the opposite head 5' being in yielding contact with the opposite face of the roll according to the 60 degree of tension imposed on the spring 7, it being possible to regulate this tension by a proper shifting of the ring 8, and thus regulate to a nicety the friction under which the paper is allowed to unwind from the roll.

65 The tension should be so regulated that in

ordinary service the section of the strip between the roll and the rear end of the guide sheet 17 shall be maintained taut; or in other words, the roll must not be so loose on the spindle as to permit its momentum to carry 70 it forward after a section of the strip has been severed by the knife. The cutter-carrying frame 12 is provided with a transversely disposed guide rod 12' at a point below the upper horizontal member of the 75 frame, said rod insuring the retention of the free end of the tape (which is to be seized by the fingers of the clerk) in front of the frame, and within reach when occasion arises to use the tape. 80

The operation is substantially as follows:—The roll of paper or tape being mounted on the spindle 3, between the heads 5, 5' (which are adjustable on the spindle to accommodate any width of tape between 85 them), the end of the tape is brought under the rear end of the guide-sheet 17, thence through the passage-way between it and the rear wall of the tank 4, thence pulled over the apron 14 and drum 11 (which dips into 90 the water in the tank 4). The gummed side of the tape is thus moistened, and when a sufficient length has been unwound, the tape is lifted against the knife edge and severed by a deft lateral movement across the edge 95 of the knife 13. The small projecting portion of the tape or stub *d* (Figs. 2, 5) left unsevered between the lip *u* and the knife is practically dry (the apron 14 having prevented contact thereof with the wet drum 100 11) and being comparatively stiff, it tends to assume a direction which it would naturally follow if not deflected therefrom by the operator when pulling the tape across the moistening drum. This direction is that 105 which is defined for it at the outlet from the passage-way aforesaid, by the lip *u* pressing against the front vertical wall of the groove *a*, between which wall and the lip *u* the tape is constrained to pass. The recoil of this dry 110 portion of the tape toward the position which is would thus naturally assume if not deflected therefrom, lifts it away from the drum, so that the free end of the tape is always left practically dry and does not stick 115 to the fingers when the next section is drawn from the roll. It will thus be seen that the permanent retention of the end of the tape from off the wet drum is due solely to the recoil of an inherently resilient strip or tape. 120

and no special devices are resorted to to pull or move the end of the tape away from the drum. Of course, a tape of limp material, or too limp to sustain its own weight without dropping would not operate successfully 125 with the present machine. In that event special devices would have to be resorted to to move the end of the tape away from the drum.

By "tape" I do not wish to be limited to 130

any particular width of paper or other material, the expression contemplating any sheet supplied from any source (a roll or otherwise). Neither do I wish to limit myself to the precise structural details here shown. For example, the apron 14 may be formed as an integral extension of the upper curved end of the rear wall of the water tank, instead of forming a separate strip as here shown. Again, the width of the sheet 17 need not necessarily correspond to the full width of the rear wall of the tank. Again, the groove *a* need not necessarily be angular in cross-section, so long as the wall thereof co-operates with the terminal of the guide sheet 17 in such a way as to tend to direct or permanently hold deflected the free end of the tape away from the moistening drum (and apron 14).

20 Other changes might be made without departing from the spirit of the invention.

In Fig. 2, the different positions of the tape are illustrated, viz., (1) that showing the tape passed over the moistening drum; (2) that showing the tape in the act of being severed by the cutter; and (3) the stub *d* left projecting beyond the lip *u* and automatically recoiled from the drum 11. The rod 12' prevents the stub from passing behind the frame 12 should it have any tendency to do so.

Having described my invention, what I claim is—

In a machine of the character described, a liquid container, a moistening drum thereon, an apron secured to one of the container walls and spaced from the drum, a resilient guide-sheet for the tape spaced from, and positioned outside of, the container wall carrying the apron, and forming a passage-way with said wall for the traverse of the tape, the wall aforesaid being provided with a groove disposed across the path of travel of the tape, the guide-sheet having a portion bent toward said groove and terminating at its free end in a lip bearing against a wall of the groove whereby the tape passing between said wall and lip is constrained to move or is normally directed away from, the apron and from the moistening drum, means for securing the opposite and fixed end of the guide-sheet across the path of travel of the tape, a cutter disposed lengthwise across the drum and above the same, and at a suitable distance from the apron and above the outlet from the passage-way aforesaid, the parts operating substantially as, and for the purpose set forth.

50 In testimony whereof I affix my signature, in presence of two witnesses.

SAMUEL BROWN.
